US00D994688S

(12) **United States Design Patent** (10) Patent No.: **US D994,688 S**
(45) Date of Patent: ** Aug. 8, 2023

(54) **ELECTRONIC DEVICE WITH ANIMATED GRAPHICAL USER INTERFACE**

(71) Applicant: **Apple Inc.**, Cupertino, CA (US)

(72) Inventor: **Mischa McLachlan**, San Francisco, CA (US)

(73) Assignee: **Apple Inc.**, Cupertino, CA (US)

(**) Term: **15 Years**

(21) Appl. No.: **29/845,822**

(22) Filed: **Jul. 11, 2022**

Related U.S. Application Data

(63) Continuation of application No. 29/769,536, filed on Feb. 5, 2021, now Pat. No. Des. 957,420, which is a continuation of application No. 29/684,732, filed on Mar. 22, 2019, now Pat. No. Des. 910,050.

CLAIM

The ornamental design for an electronic device with animated graphical user interface, as shown and described.

DESCRIPTION

FIG. 1 is a front view of a display screen or portion thereof with animated graphical user interface showing a first image of the claimed design;

FIG. 2 is a second image thereof;

FIG. 3 is a third image thereof;

FIG. 4 is a fourth image thereof;

FIG. 5 is a fifth image thereof; and,

FIG. 6 is a front view of an electronic device having a display screen with the animated graphical user interface of FIG. 1 applied thereto. The animated graphical user interface designs of FIGS. 2-5 may be similarly applied thereto. The outer broken lines in the figures show a display screen or portion thereof, or an electronic device having a display screen, and form no part of the claimed design. The other broken lines in the figures show portions of the animated graphical user interface that form no part of the claimed design.

The appearance of the animated image sequentially transitions between the images shown in FIGS. 1-5. The process or period in which one image transitions to another forms no part of the claimed design.

The electronic device with graphical user interface and animated graphical user interface may be, for example, a computer with displaying function. The graphical user interface or animated graphical user interface may be used for making electronic payments and for displaying electronic banking and payment information, for example, balance details, payment amounts, interest payments, payment history, etc.
